(57) **CLAIM**

The ornamental design for a vehicle lighting, as shown and described.

DESCRIPTION

FIG. 1 is a front, left perspective view of vehicle lighting showing my new design;

FIG. 2 is a left side view thereof;

FIG. 3 is a right side view thereof;

FIG. 4 is a front elevation view thereof, taken at section 4-4 of FIG. 2; and,

FIG. 5 is a front, left perspective view thereof in the context of an unclaimed vehicle.

Contrast in materials is shown by line shading and stipple shading in other areas.

The broken lines showing a vehicle represent environmental structure; the dot-dash lines indicate the section 4-4; all other broken lines illustrate portions of the vehicle lighting. The broken lines form no part of the claimed design.

1 Claim, 5 Drawing Sheets
